UNITED STATES PATENT OFFICE.

AUGUSTUS W. DRAKE AND WILLIAM I. RAVERT, OF LATTIMER MINES, PENNSYLVANIA; SAID RAVERT ASSIGNOR TO SAID DRAKE.

DRILLING-MACHINE.

1,035,428.

Specification of Letters Patent. Patented Aug. 13, 1912.

Application filed September 12, 1910. Serial No. 581,554.

To all whom it may concern:

Be it known that we, AUGUSTUS W. DRAKE and WILLIAM I. RAVERT, citizens of the United States, residing at Lattimer Mines, in the county of Luzerne and State of Pennsylvania, have invented a new and useful Drilling-Machine, of which the following is a specification.

The invention relates to drilling machines for boring artesian wells and holes for various purposes in and around mines, quarries, etc.

The object of the present invention is to improve the construction of drilling machines, and to provide a simple, efficient and comparatively inexpensive rotary drilling machine, designed principally for core drilling, and equipped with a main hoisting low speed drum of sufficient power to enable it to be used to lower tools and rods into the bore hole preparatory to drilling, and to hoist the same to the surface when the core barrel is filled and for other purposes, and adapted to be connected with the drill spindle when the same is in use, and capable of ready operation independently of the means for rotating the spindle to frequently raise and lower slightly the drilling tool at the bottom of the bore hole to facilitate the cutting of the rock and to help free the accumulated chippings as they are pumped from the bottom of the bore hole.

A further object of the invention is to equip the drilling machine with an auxiliary hoisting drum, designed to carry sufficient rope to extend to the bottom of the bore hole, and adapted to have connected with its rope various tools for driving casing, removing broken or parted rods and tools, drilling through broken strata, but particularly for removing by means of a tapered socket or holding device cores that fail to come to the surface by the usual means when a core barrel is removed, and capable of operation at a high speed when picking up a lost core or fishing out broken rods and tools and in similar operations, thereby effecting an immense saving in time and performing in a few minutes operations which require hours of labor with tubular rods and the slow process of coupling and uncoupling the same.

Another object of the invention is to produce a drilling machine having means for enabling the drill spindle and the other

working parts to be readily moved back from the bore hole in order to be out of the way when the auxiliary drum is used for performing any of its various functions.

With these and other objects in view, the invention consists in the construction and novel combination of parts hereinafter fully described, illustrated in the accompanying drawings, and pointed out in the claims hereto appended.

In the drawings:—Figure 1 is a side elevation of a drilling machine constructed in accordance with this invention. Fig. 2 is a similar view of the opposite side of the machine. Fig. 3 is a plan view. Fig. 4 is an end elevation of the front of the machine. Fig. 5 is a similar view of the drill spindle and the means for mounting the same, illustrating the pivotal adjustment of the drill spindle. Fig. 6 is a transverse sectional view on the line 6—6 of Fig. 1. Fig. 7 is an elevation of the drill plate stand. Fig. 8 is a transverse sectional view, taken substantially on the line 8—8 of Fig. 1. Fig. 9 is an elevation of the rear end of the machine. Figure 10 is a transverse sectional view on the line 10—10 of Fig. 1. Fig. 11 is a longitudinal sectional view on the line 11—11 of Fig. 6. Fig. 12 is an end view of the main hoisting drum, the shaft thereof being in section. Fig. 13 is a longitudinal sectional view of the base and the sub-base. Fig. 14 is a plan view of the sub-base. Fig. 15 is an enlarged sectional view of the friction clutch. Fig. 16 is a transverse sectional view on the line 16—16 of Fig. 15. Fig. 17 is a detail sectional view on the line 17—17 of Fig. 15. Fig. 18 is a detail view of the sectional threaded sleeve of the friction clutch. Fig. 19 is a detail view of the friction clutch thrust collar. Fig. 20 is a detail longitudinal sectional view of one end of the base, illustrating the manner of mounting the vertical engine. Fig. 21 is a longitudinal sectional view on the line 21—21 of Fig. 1. Fig. 22 is a side elevation, showing the rope of the main hoisting drum connected with the swivel of the drill spindle. Fig. 23 is a similar view, the base being moved back, the rope of the auxiliary drum being arranged for operation and the crank element of the auxiliary drum shaft being connected with the walking beam. Fig. 24 is a detail side view of the coupling device for detachably connecting the walking beam.

with the crank element of the auxiliary drum shaft. Fig. 25 is a vertical sectional view of the same. Fig. 26 is a detail vertical sectional view of the main drum brake lever and screw. Fig. 27 is an enlarged detail sectional view, illustrating the connection between the main drum brake lever and the screw. Fig. 28 is a plan view, illustrating the arrangement of the ropes of the main and auxiliary drums on the sheaves of the walking beam and derrick. Fig. 29 is a detail vertical sectional view, illustrating the construction for connecting the swivel of the drill spindle with the vertical guide of the drill plate. Fig. 30 is a horizontal sectional view of the same. Fig. 31 is a detail view of the gearing for sliding the base on the sub-base.

Like numerals of reference designate corresponding parts in all the figures of the drawings.

The specification is a disclosure of one form of the invention, while the claims define the actual scope of the invention.

In the embodiment of the invention illustrated in the accompanying drawings, the frame of the machine comprises in its construction an approximately oblong base 1, mounted on a sub-base 2 and consisting of a hollow casting having a top, bottom, side and end walls, and reinforced at intervals by transverse webs or flanges 3, slidably mounted on spaced rails 4 of the sub-base. The sub-base is substantially oblong, as clearly illustrated in Fig. 14 of the drawings, and the spaced rails, which form guides for the frame of the machine, are hollow and are formed integral with the bottom plate and are connected at intervals by transverse webs or flanges 5. The guiding rails have horizontal top portions beveled at opposite sides and provided with longitudinal slots 6 for the reception of bolts 7 for securing the base in its adjustment upon the sub-base. The bolts are inverted and have nuts 8 at their upper ends, and the base of the frame is provided in its side walls with openings 9, adapted to afford access to the nuts of the inverted bolts 7 to enable the frame to be clamped after adjustment. The openings 9 are of sufficient size to permit a wrench to be introduced into the hollow base from the exterior for operating the nuts, and any number of bolts 55 may be employed for clamping the frame on the sub-base. In practice it is preferable to provide an additional opening 9^a at a point between the last two bolts, as clearly shown in Fig. 13 of the drawings. This will enable the rear bolt to be used should the rearward adjustment of the frame carry the rearmost opening beyond the sub-base. The bottom of the base 1 is provided at its lower face with parallel integral ribs 10, forming grooves to receive the transversely tapered

or beveled upper portions of the guiding rails and beveled at their inner side edges to conform to the configuration of the same. The bottom of the sub-base is extended laterally beyond the guiding rails to form longitudinal projecting ledges or flanges 11, and perforated bosses or enlargements 12 are provided at intervals along the flanges 11 for the reception of bolts, or other suitable fastening means for securing the sub-base to the sills or other frame-work upon which the machine is mounted at the place where it is to be operated. The front end of the sub-base is provided with an approximately semi-circular recess 13, and is flared at opposite sides of the same and is adapted to extend partially around the bore hole and to support the frame of the machine at opposite sides thereof. The frame of the machine is slideable backwardly and forwardly toward and from the bore hole to enable a drill spindle 14 to be arranged over the same and also to be carried backwardly out of the way of the bore hole to expose the latter to permit operations other than drilling to be performed, as hereinafter fully explained. The bottom of the base is provided with a central series of drain openings 15, and the sub-base is provided with central and side drain openings 16 and 17, the side drain openings being located at the bottom of the hollow guiding rails.

The backward and forward adjustment of the frame of the machine on the base is effected by means of horizontal racks 18, located at opposite sides of the sub-base and supported by brackets 19 and meshing with opposite pinions 20, keyed or otherwise secured to a transverse shaft 21. The transverse shaft, which extends across the base, is journaled in suitable bearings of the same, and it projects at one end beyond the adjacent pinion to form a pivot for an oscillatory operating lever 22. The operating lever is suitably secured to the extended pivot portion of the transverse shaft, and it carries a pivoted reversible gravity acting pawl 23, arranged to engage the adjacent pinion for rotating the transverse shaft 21. The pawl is pivoted at its upper or outer end to the inner side or face of the operating lever, and it has opposite engaging portions at its other end, adapted to extend between the teeth of the adjacent pinion for connecting the lever with the same. The pawl is adapted to extend from either side of the lever to engage with the co-acting pinion, and its engaging portions are oppositely beveled and present an engaging shoulder to and are adapted to rotate the pinion when the pawl is moved forwardly, and they present a beveled face or edge to the pinion and are adapted to ride over the same when the pawl is moved backwardly. This renders the pawl automatic in its oper-

70

- ation when rotating the pinion in either position. The bracket 19 consists of a vertical longitudinal attaching portion and a horizontal supporting portion, projecting 5 from the upper edge of the attaching portion and braced by vertical webs or flanges 24. The horizontal supporting portion is provided at its ends with upwardly projecting transverse lugs 25, and the rack 18 is 10 fitted between the lugs 25 and is secured to the bracket by bolts, or other suitable fastening devices, which pierce the rack and the horizontal supporting portion of the bracket.
- 15 The base is limited in its sliding movement on the sub-base by means of front and rear stops 26, consisting of vertical lugs, formed integral with the front side wall of the sub-base and projecting from the outer 20 face thereof and co-acting with the plate 27, detachably secured by bolts 28 to the base and depending therefrom and operating in the space between the stops 26 and adapted to abut against the same. The plate 27 is 25 detachable, and by removing all the bolts but one, it may be swung out of the plane of the stops 26 to permit the base to slide all the way back or off the sub-base.
- The base of the frame is equipped with 30 front, intermediate and rear supporting portions or pedestals 29, 30 and 31, upon which are mounted a drill plate stand 32, and intermediate and end engine stands 33 and 34, having alined bearings consisting of 35 castings and provided at their lower ends with base plates, which are bolted or otherwise secured to the upper faces of the pedestals 29, 30 and 31, which extend across the base and are provided with flat upper faces 40 to receive the said stands. The stands are provided at their top with alined bearings 35, 36 and 37, receiving an engine shaft 38, disposed horizontally and extending longitudinally of the frame of the machine 45 throughout the entire length of the same. The drill plate stand has a circular top bearing portion or head 39, and the bearing 35 consists of an opening arranged centrally of the bearing portion 39. The bearings 36 50 and 37 consist of recesses, and the engine shaft is secured in the same by caps 40, bolted or otherwise secured to the stands and completing the bearings 36 and 37. The circular bearing portion 39 of the drill stand 55 is provided in its front face with a recess 41, and it has an annular bearing face 42, surrounding and arranged concentric with the recess and the central bearing 35 and receiving an adjustable drill plate 43.
- 60 The drill plate, which is fitted against the front annular bearing face of the drill stand, is provided at its inner face with an annular flange 44, fitting in a peripheral recess 45 of the bearing portion of the drill stand and 65 interlocking the parts against vertical move-
- ment to assist in supporting the drill plate and to relieve of strain fastening bolts 46 for adjustably securing the drill plate to the drill stand.
- The drill plate, which is annular, is provided at intervals with short arcuate slots 47 to receive the bolts, which extend through perforations 48 of the drill stand, two sets of perforations being provided so as to accommodate the drill plate in any adjustment thereof without weakening the same by relatively long slots. The bolts have their nuts arranged at the outer face of the drill plate and are readily accessible for adjusting the latter. The adjustment of the drill plate enables the drill spindle to be arranged either in a vertical position or at an inclination, and it permits an adjustment of the drill spindle to obtain a true vertical bore when the supporting surface upon which the machine is placed is not level.
- The drill plate is provided at the top and bottom with upper and lower alined sectional bearings 49 and 50, equipped with bushings 51 of bronze, or other suitable material. The drill spindle, which is slideable through the upper and lower bearings of the drill plate, is provided at opposite sides with key ways 52, receiving opposite keys 53 of a bevel gear 54, and having enlarged portions 55 at their upper ends to admit of the removal of the keys, which have outwardly projecting upper and lower terminal portions for engaging the bevel gear 54 at the top and bottom thereof. The bevel gear 54, which is preferably constructed of steel, is seated upon the bushing of the lower bearing 50 of the drill plate and meshes with a bevel gear 56, preferably constructed of bronze and formed integral with a sleeve 57, which is arranged within the central bearing 35 of the upper portion of the drill stand, and which constitutes a bearing for the engine shaft when the latter rotates, and the bevel gear 56 is disconnected from the same through the operation of a drill spindle clutch 58. The bronze bevel gear 56 meshes with the steel pinion 54 to lessen the friction, as it has been found by experience that there is less friction when one of the wheels is constructed of steel and the other of bronze than when both gears are made of the same material. The sleeve 57 also rotates within a bushing 59, fitted within the bearing 35 and provided at its front or outer end with an annular flange 60, located within the recess 41 of the bearing portion of the drill stand and secured to the bearing portion by screws, or other suitable fastening devices, as clearly shown in Fig. 11 of the drawings.
- The bushing 59 may be constructed of any suitable material, and the sleeve 57 of the bevel gear 56 is provided at its inner end with an annular enlargement having a

125 130

clutch face 61, co-acting with a clutch face 62 of the drill spindle clutch 58. The drill spindle clutch 58 is slidably interlocked with the engine shaft by means of opposite keys 63, mounted on the shaft and fitting in corresponding grooves of the drill spindle clutch 58. The drill spindle clutch 58 is limited in its sliding movement by a set collar 58^a, and it is provided with an annular 10 groove receiving a thrust collar 64 and having upper and lower projecting pivots operating in slots of a forked portion 65 of a clutch operating lever 66, disposed horizontally and extending outwardly from the drill spindle clutch and pivoted at a point intermediate of its ends in a bifurcation of a bracket 67 by a bolt 68. The bracket, which supports the operating lever 66, consists of a horizontal top portion, a vertical attaching 15 portion and a vertical bracing rib or flange. The attaching portion is bolted or otherwise secured to a flat surface at the rear face of the upper bearing portion of the drill plate stand, and the horizontal top portion is provided with a plurality of perforations 69, for the reception of a pin 70, connected with the bracket 67 by a chain and adapted to engage a registering perforation of the clutch operating lever 66. The pin is adapted to 20 hold the sliding clutch in or out of engagement with the clutch face of the gear 56. The teeth of the clutch face 62 are shouldered at their front side edges in the direction of movement for rotating the drill spindle, and they are beveled at their ends and are provided at their rear edges with slight shoulders 71, adapted to overcome the tendency to disengage the clutch face of the bevel gear due to back lash.

25 The longitudinal engine shaft is rotated by a vertical engine mounted upon the base of the frame and carried by the latter in its backward and forward movements on the sub-base, so that the connections between the engine and the main longitudinal or engine shaft 38 are not affected by such movements. The engine is located in the space between the intermediate and end engine stands 33 and 34, and it comprises in its construction 30 a pair of vertical cylinders 72, spaced apart and having an integral valve chest interposed between the cylinders. Either steam or compressed air may be used as a motive fluid for operating the engine, but an electric 35 or other motor may be mounted on the frame for rotating the main longitudinal shaft. The motive fluid is introduced through a feed or supply pipe 73, provided with a suitable throttle valve 74 and also having a 40 valve, which is automatically controlled by a governor 75. The motive fluid is exhausted through a pipe 76, having a central depending portion and horizontally disposed branches, which are connected with the vertical cylinders. The piston rods 77 recipro-

cate vertically and are connected by short connecting rods 78 with cranks 79 of the engine shaft 38, suitable cross heads being connected with the piston rods and operating in vertical guides 80 of an upright cross head frame 81. The cross head frame, which is rigidly secured to the vertical cylinders, is provided at an intermediate point between the cross head guides 80 with a guide 82 for the stems 83 of suitable slide valves, which operate in the valve chest of the engine for controlling the admission and exhaust of the motive fluid. The valve stems are connected with rods 84 of eccentrics 85, mounted on the engine shaft and operating in the usual manner to reciprocate the slide valves. When the engine is operated the main longitudinal shaft 38 is rotated. The vertical cylinders and the intermediate valve chest are connected with a horizontal drain pipe 86 by vertical branches, having suitable valves 87 and 88 for opening and closing the drain pipe connections. The drain pipe is located within the hollow base and preferably extends from the rear end thereof, and the valves are provided with elongated valve stems 89 and 90, extending through the front wall of the hollow base and provided with hand wheels, or other suitable operating means. The valve stem 90 of the valve, 95 which is connected with the steam chest, is set at an angle to clear the exhaust pipe 76, and the drain pipe controlling means may extend to any other portion of the machine.

As the specific construction of the engine 100 does not constitute a portion of the present invention and as any preferred type of motor may be employed, further description of the details of the engine structure is deemed unnecessary. The governor may also be of 105 any preferred construction, and it is connected with the engine shaft by a belt 91, arranged on pulleys 92 and 93 mounted, respectively, on the engine shaft and on a horizontal shaft of the governor. The governor 110 operates in the ordinary manner to automatically control the flow of motive fluid to the engine and thereby regulates and renders uniform the speed of the drilling machine. The rear end of the engine shaft 115 38 is preferably equipped with a fly wheel 94.

The main longitudinal shaft carries a clutch controlled spur pinion 95, provided at one side with an integral cylindrical extension 96 and formed integral with a conical shell or clutch member 97, located at the other side of the pinion and consisting of a disk and an inclined or conical rim, having an interior friction face and adapted to be engaged by an annular series of wooden 120 blocks or shoes 98, bolted or otherwise secured to a sectional ring 99 and tapered to present a conical face to the interior of the shell 97. The periphery of the sectional ring 125 is provided with transverse ribs 100, inter-

posed between the blocks or shoes and spacing the same and forming an annular series of recesses or seats to receive the said blocks or shoes. The ring 99 is also provided at 5 its periphery with a projecting annular rib 101, engaging the blocks or shoes at the outer ends of the same and fitting in recesses thereof, as clearly shown in Fig. 15 of the drawings. The sectional ring is provided 10 at a point intermediate of the inner and outer edges with an inwardly extending annular attaching flange 102, which is bolted to an annular flange 103 of an inner supporting member slidably interlocked 15 with the engine shaft by a key 104 and movable longitudinally thereof to engage the blocks or shoes with the rim of the shell and to carry them out of such engagement. The inner supporting member is provided 20 with an annular groove, receiving a sectional thrust collar 105, provided with projecting ears 106 having threaded openings for the reception of screws 107 for adjustably connecting the thrust collar with a sectional 25 clamping collar 108. The connecting screws 107, which are located at diametrically opposite points, pass through perforations of a projecting ear 109 and an operating arm or lever 110, and are provided with nuts 30 111 and 112 for securing the screws 107 to the clamping collar and for also engaging the ears 106 of the thrust collar to lock the screws in their adjustment. The sectional clamping collar is provided with an interior 35 annular groove 113, and is fitted tightly on a rotary nut 114, which engages a threaded sleeve 115. The sleeve 115 is split longitudinally to form two sections, and it is secured within the bearing of the intermediate 40 engine stand, being rigidly clamped in the recess thereof by the cap or upper section of the bearing. The nut 114 is provided with a peripheral rib 116 to fit the annular groove 113 of the clamping collar, 45 and it is adapted to be rotated on the sleeve 115, which is threaded and supported in the bearing of the intermediate engine stand, being preferably provided with triple threads to secure a rapid movement of the 50 clutch. The screws 107 are adapted to be adjusted to take up the wear of the blocks or shoes to secure the proper frictional contact between the engaging members of the clutch. The operating arm or lever extends 55 outwardly and forwardly and is provided at its outer end with a grip or handle, which is arranged in convenient position to enable the operator to grasp simultaneously both the arm or lever 110 and the drill 60 spindle clutch lever. The clamping collar is also equipped with a counter-weight 117, adjustably mounted on an inclined rod 118, which extends upwardly from the clamping ring in the opposite direction from the operating arm or lever. A longitudinally split

bushing 119 is arranged on the engine shaft to receive the pinion 95, and it is provided at its forward or outer end with an annular flange, which fits against the outer end of the cylindrical extension of the pinion, and is secured thereto by screws, or other suitable fastening devices. The shell of the friction clutch and the pinion are held against longitudinal movement by means of collars 120 and 121, mounted on the shaft and secured to the same by set screws. The collar 120 is located within the shell of the friction clutch, and the other collar 121 is arranged at the outer end of the bushing 119.

The spur pinion of the engine shaft meshes with an intermediate gear wheel 122, mounted on an auxiliary drum shaft 123, journaled in suitable bearings 124 and 125 of the drill plate stand and the intermediate engine stand and carrying an auxiliary high speed drum 126. Motion is communicated from the auxiliary drum shaft to a main hoisting low speed drum shaft 127 by means of a pinion 128, fixed to the auxiliary drum shaft and meshing with a large gear wheel 129, mounted on the main drum shaft 127. The auxiliary drum shaft is located at the rear side of the machine at the upper portion of the frame, and the bearings 124 and 125 are sectional, being provided with removable caps. The shaft 127, which carries a main hoisting low speed drum 130, is located at the front of the machine in a plane below the auxiliary drum shaft, and is journaled in suitable bearings 131 and 132, which are also sectional, and the drill plate stand is provided opposite the bearing 131 with an opening 133, adapted to enable a worn-out bushing to be quickly replaced or to permit the main hoisting drum shaft to be readily introduced into and removed from its bearings.

The gearing for connecting the main drum shaft with the engine shaft reduces 110 the speed and increases the power sufficiently to enable the main drum to control the rod, and the main drum is located between the large gear 129 and a set collar 134, which holds the main drum against 115 movement longitudinally of the shaft 127. The main drum is provided at one end with a friction flange 135, which is engaged by a brake band 136, connected at its ends by a link 137 and an adjusting rod 138 with a 120 brake lever 139, extending beneath a main drum and pivoted at its rear end to a brake lever stand 140 by a horizontal pin 141. The brake lever stand is bolted, or otherwise secured upon the base of the frame adjacent to the pedestal or supporting portion 134 at the front end of the base. The adjusting rod 138 is composed of adjustable sections and is adapted to adjust the brake band to take up the wear and cause the band 125 130

to properly engage the friction flange of the drum. The brake band is supported at an intermediate point by a vertical screw 142, pivoted at its lower end to the brake band between spaced ears thereof, and having its other end piercing a horizontal spring 143 and adjustably connected with the same by nuts 144, engaging the upper and lower faces of the spring. The spring 10 is secured to and projects from a supporting bracket 145, which is mounted on the drill plate stand at the inner face of the upper bearing portion thereof. The spring 15 yieldably supports the brake band out of engagement with the drum when the brake is not applied.

The brake lever 139 is equipped at its rear end with an adjustable counter-weight 146, and it is provided at its front end with 20 a foot receiving plate or portion 147, and is adapted to be depressed by the foot of the operator to apply the brake band. In order to enable the main drum band brake to be applied with sufficient force to control a 25 heavy load, the machine is equipped with an operating screw 148, arranged vertically above the brake lever 139 and mounted in a pivotal nut 149 and provided in its lower portion with a longitudinal bore or 30 socket 150 for the reception of a stem 151 of a yoke 152. The yoke 152 is pivoted in a flanged opening 153 of the brake lever, and the stem and the bore form a loose slide- 35 able connection between the screw and the brake lever and permit the brake lever to be operated independently of the screw to apply the brake, when the foot of the operator is sufficient to control the rod. The nut 149 is formed integral with a horizontal 40 pivot 154, mounted in a horizontal bearing 155 of a bracket 156, and threaded at its extremity to receive a nut 157 for securing the pivot in the bearing of the bracket. The bracket is bolted, or otherwise secured to the 45 front side face of the pedestal or supporting portion 29 of the base of the frame. The upper end of the brake operating screw 148 is equipped with a hand wheel, and when it is rotated to apply the brake, the lower 50 end of the screw engages the yoke 152 and forces the brake lever 139 downward and applies pressure to the friction flange of the drum. The auxiliary high speed drum 126 is constructed substantially the same as 55 the low speed drum, and it is provided with a friction flange 158, which receives a brake band 159, connected at its terminals at the bottom of the auxiliary drum with a rocker arm 160 by a link 161 and an adjusting rod 60 162. The brake band 159 is yieldably supported at the top by a horizontal spring 163, adjustably connected with the brake band by a vertical screw 164 and mounted on a supporting bracket 165. The screw is piv- 65 otally connected with the brake band and

is adjustably secured to the spring by nuts 166, and the supporting bracket 165 is secured to the inner face of the upper bearing portion of the drill plate stand.

The rocker arm 160 is mounted on a horizontal pivot 167, and it has a depending portion, which is connected by an inclined link 168 with a brake lever 169, pivoted in the brake lever stand 140 by the horizontal pin 141 and provided at its rear end with a counterweight 170. The horizontal pivot 167 is carried by the drill plate stand, and the auxiliary drum brake lever extends forwardly from the brake lever stand to the front of the machine and has a depending 75 front portion, equipped with a pair of foot plates 171, extending in opposite directions and having upwardly extending shanks or attaching portions, secured to the lever 169 at opposite sides thereof. While only a 80 brake lever is shown for applying the band brake of the auxiliary drum, it will be readily understood that the drilling machine may also be equipped with a screw, constructed similarly to that heretofore described and arranged to actuate the brake lever 169.

The main drum 130 is provided with a clutch face 172, located within the friction flange 135 and co-acting with a movable clutch 173, slidably interlocked with the main drum shaft 127 by a key 174, and provided with an annular groove for the reception of a thrust collar 175. The thrust collar 175 is connected by opposite pivots 176 with a forked portion 177 of a clutch operating lever 178. The clutch operating lever 178 is pivoted in a bifurcation of a supporting bracket 179, and is adapted to be oscillated horizontally to actuate the main drum clutch, which is secured either in or out of engagement by a pin 180, preferably connected with the supporting bracket 179 by a short chain. The supporting bracket 179 is bolted or otherwise secured to the drill 100 plate stand, and the pin is adapted to engage perforations of the bifurcated portion of the bracket and the clutch operating lever. The friction flange 135, which is arranged in 105 spaced relation with the clutch face 172, extends outwardly beyond the same, and it may be utilized in connection with an expanding clutch of any preferred construction, which may be arranged to engage the inner face of the friction flange to lock the 110 main drum to the shaft 127.

The auxiliary drum is provided with a clutch face similar to that of the main drum and is locked to its shaft 123 by a sliding clutch 181, pivotally connected with a 125 forked portion 182 of a clutch operating lever 183, fulcrumed at an intermediate point in a bifurcation of a supporting bracket 184. The supporting bracket 184 is mounted upon the drill plate stand, and the clutch operat- 130

ing lever 183, which is horizontally movable to engage the clutch 181 with the auxiliary drum, is locked in either position by a pin 185. The clutch operating levers of the 5 main and auxiliary drums and the drill spindle are located at the inner face of the drill plate stand, and are in convenient position to be grasped by the operator simultaneously with the friction clutch arm or lever 10 110, so that the operator may hold the friction clutch arm or lever with one hand and operate any one of the clutch levers with the other hand, whereby the machine is under complete control of the operator, who 15 does not have to change his position at the front of the machine to control any of the working parts of the drilling machine.

The main low speed drum carries a relatively heavy wire rope 186 of sufficient 20 length to pass over an over-head pulley or sheave 187 and extend to the surface where the drilling begins, and it is employed to lower tools and rods in the bore hole preparatory to drilling and to hoist the same to 25 the surface when the core barrel is filled, or for any other purpose, the gearing, which connects the main drum shaft with the engine shaft, being adapted to lower the speed and increase the power sufficiently to enable 30 the main drum to control the load. The guide pulley or sheave 187 is preferably mounted in a horizontal shaft or spindle 188, which is carried by the front end of a walking beam 189, fulcrumed at an intermediate 35 point on the top of a derrick 190 by a transverse pivot 191. The main drum is equipped with a rope clamp 192, and the cable is preferably guided to the pulley or sheave 187 by a guide pulley 193, located above the main 40 drum, as clearly illustrated in Fig. 22 of the drawings. The derrick constitutes an over-head support for the walking beam and the shaft or spindle 188 at the front of the walking beam has extended terminal portions and projects laterally, and is adapted 45 when the main drum is in use to rest in bearings 194, mounted on the top of the derrick at opposite sides thereof and having semi-circular seats or recesses to receive the 50 shaft or pivot.

The drill spindle is equipped at its upper end with a swivel 195, having a bail 196 for the attachment of the cable 186 of the main drum and provided with a horizontal projecting portion 197, extending from the 55 swivel plate 198 and operating in a vertical guide 199 to prevent rotary movement of the swivel and the twisting of the rope. The water and shot are introduced into the 60 tubular rods at the lower end of the spindle to avoid wetting the machine and the operator and to prevent chilled shot from getting into the machine and damaging the same. The swivel 195 is of the ordinary 65 construction, and the horizontally project-

ing portion 197 is equipped with an anti-friction sleeve, or other suitable anti-friction device. The guide, which receives the projecting portion of the swivel, extends upwardly from the top of the drill plate and 70 is composed of spaced sides, connected at the top of the guide, which is bolted or otherwise secured to attaching flanges 200 of the drill plate. The guide is carried by the drill plate in the adjustment thereof and 75 the sides of the guide are provided at the front with longitudinal flanges 201, adapted to reinforce the guide and presenting flat surfaces to the swivel. When the drill spindle is rotated during the operation of the 80 machine, the cable of the main drum is connected to the swivel 195 to frequently raise and lower slightly the drilling tool at the bottom of the bore hole to facilitate the cutting of the rock and to help free the accumulated chippings as they are pumped from the bottom.

The auxiliary high speed drum carries a wire rope 202 of sufficient length to pass over an over-head sheave or pulley 203 and extend to the bottom of the bore hole. The pulley or sheave 203 is mounted on the shaft or spindle 188 in spaced relation with the sheave 187, and is guided to the same by a pulley 204, located above the auxiliary drum and spaced from the guide pulley 193 and arranged on a shaft or spindle 205. The shaft or spindle 205 is mounted in suitable hangers 206 and supports both of the guide pulleys 193 and 204. The guiding means, 90 however, may be mounted on the derrick, or supported in any other desired manner. Various tools may be attached to the rope of the auxiliary drum for driving casing, removing broken or parted rods, drilling 95 through broken strata, and particularly for removing lost cores that fail to come to the surface by the usual means. By means of the auxiliary high speed drum, a cone-shaped socket (not shown) or other holding 100 device may be run to the bottom of a bore hole in a few minutes, and it will be apparent that the auxiliary drum is adapted to effect an immense saving of time and labor in such operations over the old way of 105 using the rods with the slow process of coupling and uncoupling.

The auxiliary drum shaft is equipped at its inner end with a crank element 207, preferably consisting of a crank disk and wrist 110 pin, and adapted to be connected with the rear end of the walking beam by a wire rope 208, or other suitable flexible connection to impart an oscillatory movement to the walking beam to actuate the same to form a 115 churn drill for drilling broken strata, and in other places where shot drilling is impracticable. When used for this purpose, the rope of the auxiliary drum is equipped with 120 a set of tools and drill jars, and the flexible 125

connection 208 is of a length to permit the shaft or spindle 188 at the forward end of the walking beam to come within a short distance of the bearings 194, and it prevents the said shaft or spindle 188 from striking the bearings during the oscillation of the walking beam. When the drums are employed for hoisting and when the drill spindle is rotated, the forward arm of the walking beam is lowered to permit the shaft or spindle 188 to rest firmly in the bearings 194.

The oscillation of the walking beam through the rotary movement of the auxiliary drum shaft is effected independently of the rotation of the auxiliary drum, which during such drilling, is uncoupled from the shaft 123 and is held fast by its band brake. The rope 202 is held fast at the auxiliary drum and the up and down movement of the walking beam is sufficient for operating the drilling tool, as the rope 202 in passing upward over the sheave or pulley 203 is given a quick lift and a quick drop, and the rope 25 is permitted to drop approximately twice the distance of the travel of the walking beam. This movement is further increased by the lengthening of the forward arm of the walking beam. When the auxiliary drum is used 30 for any of its various operations, the frame of the machine and the working parts are moved back on the sub-base by the gearing heretofore described, which arranges the drill spindle out of the way and exposes the bore 35 hole.

The rope 208 is connected at its upper end with the rear end of the walking beam by any suitable means, and its lower end is looped around a coupling device 209 for 40 detachably connecting the rope 208 with the crank element. The wrist pin 210 of the crank element 207 is provided at its outer end with a head or flange, and is equipped with a sleeve or bushing 211, provided with an annular groove 212, which is engaged by a spring actuated bolt 213 of the coupling device 209. The coupling device consists of a tapered block or casing, grooved to receive the loop 214 of the rope 45 208, and bored for the reception of the spring actuated bolt, which is reduced at its engaging portion to fit the groove 212 of the sleeve or bushing. The bolt is operated by a stud or pin 215, projecting through a slot in the casing or body portion of the coupling device and adapted to be operated 50 to disengage the bolt from the sleeve 211. The sleeve is flush with the head or flange of the wrist pin and when the bolt is retracted, 55 the coupling device is adapted to be readily placed on or removed from the wrist pin. The lower looped end of the rope 208 is secured by a suitable rope clamp 216.

The lower end of the drill spindle is connected with the tubular rods by a coupling

217, having a pipe connection 218 for connecting it with a pump (not shown) and for introducing shot, but as this coupling forms the subject-matter of a companion application, filed Sept. 12, 1910, Serial No. 581,547, 70 detail description and further illustration of this construction is deemed unnecessary.

The machine is equipped with guards 219 and 220 for the gearing, which communicates motion from the engine shaft to the 75 main and auxiliary drums. The guards 219 and 220 consist of bars and extend along the exterior of the gearing in spaced relation with the same, and are secured at their terminals to the frame at opposite sides thereof, as clearly shown in Fig. 8. In practice the machine will also be provided with a 80 guard for the bevel gear 54 of the drill spindle.

Having thus fully described our invention, 85 what we claim as new and desire to secure by Letters Patent, is:—

1. A drilling machine comprising a sub-base provided with spaced guiding rails, a frame having a base mounted on and 90 slideable along the guiding rails and being of a width less than the width of the sub-base, longitudinal rack bars fixed to the sub-base at opposite sides thereof and located outside of the guiding rails, a shaft journaled in 95 and extending across the frame and projecting at opposite sides thereof, pinions mounted on the projecting portions of the shaft and meshing with the rack bars, a lever pivotally mounted on the shaft at one end 100 thereof, and a pawl carried by the lever and arranged to engage the adjacent pinion for rotating the shaft to slide the frame along the sub-base.

2. A drilling machine including a sub-base 105 provided with guides and having longitudinal slots, a frame having a hollow base supported on the guides and provided with openings, interiorly arranged bolts mounted on the hollow base at the openings 110 thereof and operating in the slots of the sub-base for securing the frame in its adjustment, and drilling mechanism carried by the frame.

3. A drilling machine including a sub-base 115 consisting of a bottom plate, spaced hollow guiding rails formed integral with the bottom plate and provided with slots, and transverse webs connecting the guiding rails and formed integral with the same and 120 with the bottom plate, a frame having a base supported on the guiding rails, fastening means carried by the frame and operating in the slots of the sub-base for securing the frame in its adjustment, and drilling 125 mechanism carried by the frame.

4. A drilling machine including a sub-base provided with spaced hollow guiding rails having longitudinal slots, said sub-base being also provided at the bottom with 130

5 drain openings, a frame having a hollow base supported on the guiding rails and provided with drain openings, drilling mechanism carried by the frame, and means for moving the frame backward and forward along the guiding rails.

10 5. A drilling machine including a frame, a main longitudinal shaft mounted on the frame, a drill spindle carried by the frame and arranged at the front end of the said shaft, a motor also carried by the frame and operatively connected with the rear portion of the shaft, a main low speed hoisting drum, an auxiliary high speed hoisting drum, said drums being disposed longitudinally of the frame and located between the motor and the drill spindle, and gearing for communicating motion from the longitudinal shaft to the drums and to the drill spindle.

15 6. A drilling machine including a frame, a main longitudinal shaft mounted on the frame, a drill spindle carried by the frame and arranged at the front end of the said shaft, a motor also carried by the frame and operatively connected with the shaft at the rear end thereof, a main low speed hoisting drum, an auxiliary high speed hoisting drum, said drums being disposed longitudinally of the frame and located at opposite sides of and below the plane of the longitudinal shaft, and gearing for communicating motion from the longitudinal shaft to the drums and to the drill spindle.

20 7. A drilling machine including a frame, a main longitudinal shaft mounted on the frame, a drill spindle carried by the frame and arranged at the front end of the said shaft, a motor also carried by the frame and operatively connected with the rear portion of the shaft, a main low speed hoisting drum, an auxiliary high speed hoisting drum, said drums being disposed longitudinally of the frame and located between the engine and the drill spindle, gearing for communicating motion from the longitudinal shaft to the drums and to the drill spindle, and independent clutches for throwing the drums and the drill spindle into and out of operation.

25 8. A drilling machine including a frame, a main longitudinal shaft mounted on the frame, a drill spindle carried by the frame and arranged at the front end of the said shaft, a motor also carried by the frame and operatively connected with the rear portion of the shaft, a main low speed hoisting drum, an auxiliary high speed hoisting drum, said drums being disposed longitudinally of the frame and located between the engine and the drill spindle, gearing for communicating motion from the longitudinal shaft to the drums and to the drill spindle, independent clutches for throwing the drums and the drill spindle into and out of

operation, and independent means for holding the drums against rotary movement.

30 9. A drilling machine including a frame, a main longitudinal shaft, a drill spindle arranged at the front end of the shaft, gearing for communicating motion from the longitudinal shaft to the drill spindle, a motor mounted on the frame and operatively connected with the longitudinal shaft and spaced from the drill spindle, main and auxiliary drums extending longitudinally of the shaft at the space between the engine and the drill spindle, and gearing connecting the drums with the longitudinal shaft and arranged to rotate the said drums at different speeds.

35 10. A drilling machine including a frame composed of a base, spaced stands mounted on the frame at the ends thereof and at an intermediate point and provided with alined bearings, a main longitudinal shaft journaled in the said bearings, a drill spindle arranged at the front end of the longitudinal shaft, gearing for connecting the drill spindle with the said shaft, a motor mounted on the rear portion of the frame in the space between the intermediate stand and the rear end stand and operatively connected with the longitudinal shaft, main and auxiliary drums arranged longitudinally of the shaft in the space between the intermediate stand and the front end stand, and gearing connecting the drums with the longitudinal shaft and arranged to rotate the same at different speeds.

40 11. A drilling machine including a frame comprising a base provided at its ends and at an intermediate point with pedestals, a drill plate stand located at the front end of the frame and mounted on one of the end pedestals, engine stands mounted on the other pedestals, a longitudinal shaft journaled in bearings of the said stands, a drill spindle arranged at the front end of the longitudinal shaft, gearing connecting the longitudinal shaft with the drill spindle, an engine mounted on the frame between the engine stand in spaced relation with the drill spindle and operatively connected with the longitudinal shaft, and a drum mounted on the frame in the space between the drill plate stand and the adjacent engine stand and connected with and actuated by the longitudinal shaft.

45 12. A drilling machine including a frame, a drill plate stand mounted on the frame and having a bearing portion provided with duplicate sets of perforations, a drill plate having spaced upper and lower alined sectional bearings, one of the sections of each of said bearings being integral with the drill plate, and the latter being fitted against the bearing portion of the drill plate stand and provided with a plurality of short slots, fastening devices operating in the slots and

- passing through the perforations and adapted to be transferred from one perforation to another, a drill spindle arranged in the bearings of the drill plate, and means for 5 rotating the drill spindle.
13. In a drilling machine, the combination with a drill spindle and a gear connected with the same, of a frame, a shaft mounted on the frame, a sleeve loose on the shaft and provided at one end with a gear to mesh with the said gear of the drill spindle and having a clutch face at its other end, and a clutch slidably interlocked with the shaft and coacting with the clutch face of the said sleeve to connect the same with and disconnect it from the shaft.
14. In a drilling machine, the combination with a drill spindle and a gear connected therewith, of a frame, a shaft mounted on the frame, a sleeve arranged on the shaft and provided at its outer end with a gear to mesh with the said gear of the drill spindle and having at its inner end an annular enlargement provided with a clutch 25 face, a bushing carried by the frame and receiving the said sleeve and arranged between and fitting against the gear and the annular flange thereof and having an attaching portion for securing it in fixed relation with the sleeve, and a clutch slidably interlocked with the shaft and coacting with the clutch face of the sleeve to connect the same with and disconnect it from the shaft.
15. A drilling machine comprising a frame, a drill spindle carried by the frame and provided with a key way having an enlarged portion, gearing for rotating the drill spindle including a gear mounted on the drill spindle, and a key slidable in the 35 key way of the drill spindle and provided with terminal projecting portions engaging the gear of the drill spindle, said key being removable through the enlarged portion of the key way.
16. A drilling machine including a sub-base, a frame movably mounted on the sub-base, a drill spindle carried by the frame and provided with a swivel, gearing mounted on the frame for rotating the drill spindle, 45 guiding means also carried by the frame and connected with the swivel for preventing rotary movement thereof, and means for moving the frame backward and forward on the sub-base to carry the drill spindle to and from the bore hole.
17. A drilling machine including a sub-base, a frame movably mounted on the sub-base, a drill spindle carried by the frame and provided with a swivel, gearing mounted on the frame for rotating the drill spindle, and a relatively fixed guide also carried by the frame and extending above the same and connecting with the swivel for preventing rotary movement of the same.
18. A drilling machine including a sub-base, a frame movably mounted on the sub-base, a drill spindle carried by the frame, a swivel connected with the upper end of the drill spindle and provided with a projecting portion, an upright guide mounted on the frame and receiving the projecting portion of the swivel to prevent rotary movement of the same, and gearing carried by the frame for rotating the drill spindle.
19. A drilling machine including a frame provided with a drill plate stand, a drill plate adjustably mounted on the stand and having spaced bearings, a drill spindle slidably in the bearings, a swivel connected with the upper end of the drill spindle, and a vertical guide mounted on the drill plate and having an opening receiving a portion of the swivel for preventing rotary movement of the same.
20. A drilling machine including a frame, a drill spindle, gearing for rotating the drill spindle, a swivel connected with the upper end of the drill spindle and provided with a projecting anti-friction device, and a relatively fixed upright guide having an opening receiving the anti-friction device of the swivel.
21. A drilling machine including a sub-base, a frame movably mounted on the sub-base, a drill spindle carried by the frame, 95 gearing mounted on the frame for rotating the spindle, a swivel connected with the upper end of the drill spindle, a coupling connected with the lower end of the drill spindle and having a pipe connection for the introduction of water and shot, means mounted on the frame for rotating the drill spindle, and means also carried by the frame and connected with the swivel for preventing rotary movement thereof.
22. A drilling machine including a sub-base, a frame movably mounted on the sub-base, a drill spindle carried by the frame, gearing mounted on the frame for rotating the drill spindle, a swivel connected to the upper end of the drill spindle, a coupling connected to the lower end of the drill spindle and having means for the introduction of water and shot, a hoisting drum mounted on the frame and having a rope attached to the swivel, and guiding means also carried by the frame and connected with the swivel for preventing the twisting of the rope.
23. A drilling machine including a frame provided with a drill plate stand, a drill plate adjustably mounted on the stand and having bearings, a drill spindle slidably in the bearings, a swivel connected with the upper end of the drill spindle, guiding means carried by the drill plate in the adjustment thereof and connected with the swivel for preventing rotary movement of the same, and a coupling connected with the lower end of the drill spindle and having means for the introduction of water and

shot, and means mounted on the frame for rotating the spindle.

24. A drilling machine including a frame composed of a base, spaced stands mounted on the frame at the ends thereof and at an intermediate point and provided with bearings, a main longitudinal shaft journaled in the said bearings, a drill spindle arranged at the front end of the frame and connected with and actuated by the longitudinal shaft, a motor mounted on the frame at the rear portion thereof between the intermediate and rear stands and located beneath and operatively connected with the said shaft, longitudinal drums located at opposite sides of the frame below the plane of the said shaft and extending longitudinally thereof, and gearing connecting the drums with the longitudinal shaft and arranged to rotate the said drums at different speeds.

25. A drilling machine including an overhead walking beam, a pulley carried by one arm of the same, a shaft having a crank element connected with the other arm of the walking beam for oscillating the latter, and a drum mounted on the shaft and having a rope arranged on the pulley of the walking beam, and means for holding the drum against rotary movement.

26. A drilling machine including a frame, main and auxiliary drums having ropes, an overhead walking beam provided at one end with pulleys receiving the ropes of the drums, a crank element connected with the auxiliary drum, and means for connecting the crank element with the walking beam for oscillating the same.

27. A drilling machine including a frame, main and auxiliary drums having ropes, a crank element connected with the auxiliary drum, a walking beam located above the drums and provided at one of its arms with pulleys receiving the ropes of the main and auxiliary drums, means for detachably connecting the crank element with the walking beam, and means for rigidly supporting the walking beam when the same is disconnected from the crank element.

28. A drilling machine including a drill spindle, a sub-base, a frame movable back and forth on the sub-base to carry the drill spindle to and from a bore hole, main and auxiliary drums also mounted on the frame and having ropes, an overhead walking beam, pulleys mounted on the walking beam and receiving the ropes of the drums, means for oscillating the walking beam to form a churn drill when the drill spindle is carried backward by the frame.

29. A drilling machine comprising a sub-base, a frame movable backwardly and forwardly on the sub-base, a drill spindle carried by the frame, main and auxiliary drums provided with ropes, shafts mounted on the

frame and supporting the drums, a crank element carried by the shaft of the auxiliary drum, an overhead walking beam, means for detachably connecting one end of the walking beam with the crank element, and a pair of pulleys mounted on the walking beam at the other end thereof and receiving the ropes of the drums.

30. A drilling machine including a frame, a drill spindle carried by the frame, means for moving the frame backwardly and forwardly to carry the drill spindle to and from a bore hole, main and auxiliary drums provided with ropes, a derrick, a walking beam pivotally mounted on the derrick, a shaft carried by one end of the walking beam, pulleys arranged on the shaft and receiving the ropes of the drums, a fixed bearing arranged to receive the shaft of the pulleys to support the walking beam in fixed position, and means for oscillating the walking beam to form a churn drill when the drill spindle is moved back from a bore hole.

31. A drilling machine including a sub-base, a frame having a base mounted for movement on the sub-base, a drill spindle carried by the frame, a main longitudinal shaft mounted on the frame and located above the base, an engine mounted on the base and located beneath and operatively connected with the longitudinal shaft, main and auxiliary drums provided with ropes and having shafts journaled in the frame, gearing connecting the drum shaft with the longitudinal shaft, other gearing connecting the longitudinal shaft with the drill spindle, a crank element connected with the auxiliary drum shaft, an overhead walking beam, means for detachably connecting one arm of the walking beam with the said crank element, and pulleys carried by the other arm of the walking beam and arranged to receive the ropes of the drums.

32. A drilling machine including a sub-base, a frame having a base mounted for movement on the sub-base, a drill spindle carried by the frame, a main longitudinal shaft mounted on the frame and located above the base, an engine mounted on the base and located beneath and operatively connected with the longitudinal shaft, main and auxiliary drums provided with ropes and having shafts journaled in the frame, gearing connecting the drum shafts with the longitudinal shaft, other gearing connecting the longitudinal shaft with the drill spindle, a crank element connected with the auxiliary drum shaft, a derrick, an overhead walking beam pivotally mounted on the derrick, means for detachably connecting one arm of the walking beam with the said crank element, pulleys carried by the other arm of the walking beam and arranged to receive the ropes of the drums, and fixed

- means mounted on the derrick for rigidly supporting the walking beam when the same is disconnected from the crank element.
33. A drilling machine including a frame, 5 a drill spindle, a swivel connected to the upper end of the drill spindle, an upright guide mounted on the frame and receiving the said swivel, a main drum mounted on the frame and having a rope connected with the swivel of the drill spindle, an auxiliary drum having a rope and provided with a shaft mounted on the frame, a crank element connected with the shaft of the auxiliary drum, an overhead walking beam, pulleys carried by one arm of the walking beam and receiving the ropes of the drums, and means for detachably connecting the other arm of the walking beam with the crank element.
34. In a drilling machine, the combination with a sub-base, of a main frame movably mounted thereon, drilling mechanism carried by the frame and including a rotary drilling tool, a walking beam pivotally supported above the drilling mechanism independently of said frame, means for moving the frame backwardly and forwardly to carry the drilling mechanism to and from the bore hole, and means for connecting the walking beam with the drilling mechanism for oscillating the walking beam to form a churn drill when the said drilling mechanism is moved backwardly from the bore hole.
35. A drilling machine including a sub-base, a frame slideable on the base, a drill spindle mounted on the frame and adapted to be carried by the same to and from the bore hole, gearing carried by the frame for 40 operating the drill spindle, a walking beam pivotally supported above the frame independently of the latter, and means for connecting the walking beam with the said gearing to oscillate the walking beam and 45 form a churn drill when the drill spindle is moved back from the bore hole.
36. In a drilling machine, the combination of a sub-base, a main frame movably mounted thereon, drilling mechanism carried by 50 the main frame and including a rotary drilling tool, a drum also mounted on the frame and carrying a cable, an over-head walking beam pivotally mounted independently of the frame and provided with a pulley adapt-
- ed to receive the cable of said drum, means 55 for moving the frame backwardly and forwardly, and means for connecting the walking beam with the drilling mechanism for operating the walking beam to form a churn drill when the drilling mechanism is moved 60 backwardly from the bore hole.
37. In a drilling machine, the combination with a movably mounted frame, drilling mechanism carried by the frame and including a rotary drilling tool, and gearing for 65 operating the same, a drum carrying a cable, an overhead walking beam pivotally mounted independently of the frame and provided with a pulley adapted to receive the cable of the drum, means for moving the frame 70 backwardly and forwardly to carry the rotary drilling tool to and from the bore hole, and means for connecting the walking beam with the gearing to form a churn drill when the said drilling tool is moved backwardly 75 from the bore hole.
38. In a drilling machine, the combination of a movably mounted frame, drilling mechanism carried by the frame and including a rotary drilling tool, gearing for 80 operating the rotary drilling tool, an overhead walking beam pivotally mounted independently of the frame and provided with pulleys, main and auxiliary drums mounted on the frame and carrying cables 85 adapted to be arranged on the said pulleys, the cable of the main drum being provided with means for connecting it with the rotary drilling tool and the cable of the auxiliary drum being provided with 90 means for attaching a tool to it for churn drilling, means for connecting the drums with and disconnecting them from the said gearing, means for moving the frame to carry the rotary drilling tool to and from 95 the bore hole, and means for connecting the walking beam with the gearing to form a churn drill when the frame is moved backwardly to carry its drilling mechanism from the bore hole.
